SEWING MACHINE

James T. Dowdall, Gloversville, N. Y., assignor, by
mesne assignments, to Elizabeth B. Straus,
Gloversville, N. Y.

Application January 14, 1937, Serial No. 120,472

4 Claims. (Cl. 112—98)

My invention relates to a new and improved sewing machine, and a new and improved method of sewing.

One of the objects of my invention is to provide a new and improved method of sewing an article, such as a sheet of cloth, or a sheet of leather, or other material which is used for making gloves, so as to provide an upstanding rib or ribs upon the surface of the work. Said rib or ribs may be of a zig-zag shape or may have any desired ornamental shape.

Another object of the invention is to provide an improved method of sewing a material having said rib construction, with the use of a multiple needle sewing machine.

While the invention is directed primarily to the sewing of gloves, it is not necessarily limited to this purpose.

Other objects of my invention are to provide a simple and efficient attachment which may be applied, for the purposes of the invention, to sewing machines of a type well known in the trade.

Other objects of my invention will be set forth in the following description and drawings which illustrate a preferred embodiment thereof, it being understood that the above statement of the objects of my invention is intended generally to explain the same without limiting it in any manner.

Fig. 1 is a side elevation showing a sewing machine to which the improved attachment is applied.

Fig. 2 is a partial top plan view of Fig. 1.

Fig. 3 is a top plan view taken on the bed plate of the machine illustrated in Fig. 1.

Fig. 4 is a detail side elevation taken at the left-hand side of Fig. 1.

Fig. 5 is a bottom plan view taken on the line 5—5 of Fig. 4.

Fig. 6 is a top plan view showing the completed work.

Fig. 7 is a sectional view of the stitched article.

Fig. 8 is a sectional view on the line 9—9 of Fig. 3.

Fig. 9 is a complete side elevation, taken at the left-hand side of Fig. 1.

Fig. 10 is a plan view on the line 11—11 of Fig. 9.

I have not illustrated the standard construction of the well known sewing machine to which the parts of my attachment are applied, as said machine is well known in the trade. Said machine is a multiple needle machine and it may have two needles or more than two needles.

I have illustrated the invention in connection with a machine having two needles. This well known machine has the head 1 and the bed plate

2. Said machine has a main driving shaft (not shown) which is provided with the usual hand wheel 3 and with the usual drive pulley 4. The needle bar 5 is mounted in the usual manner so that said needle bar is vertically reciprocated.

Referring to Fig. 9, this shows the needle bar 5 mounted slidably in upper and lower bearings 12. Said bearings 12 are integral with, or they are suitably connected to a frame 60, having spaced front and rear arms. The rear arm of the frame 60 is pivotally connected to the head 1 of the machine, by means of pivot pins 61. Parts of the shanks of said pivot pins 61 are suitably threaded, so that said pivot pins can be screwed through tapped openings which are provided in superposed portions of the head 1.

Fig. 1 and Fig. 9 show the standard means for turning the frame 60 about the vertical axis of pins 61. Such means include the top bearing-collar 12. Said top bearing 12 has a lug, and a link 7 is pivotally connected to said lug by means of the pivot pin 6. The other end of said link 7 is adjustably and pivotally connected by means of the member 8, to the grooved or slotted portion 10 of a member 9 which is pivotally connected to the head 1, by means of the pivot pin 11. The pivot connection 8 can include a wing-nut or any other suitable adjustable device so that member 8 can be adjusted and held adjusted relative to member 11, in order to vary the amplitude of movement of the frame 60.

The novel parts of my attachment include a link 15 which is adjustably and pivotally held in the groove 10 of the member 9, by means of a pivot member 14, which can be located in the groove 10 at any desired distance from the pivot member 11. Said link 15 oscillates an arm 17 to 40 which the link 15 is pivotally connected by means of the member 16. The arm 17 also forms a part of the novel attachment and it is pivotally connected at 18 to a plate 19 which is connected by means of screws 20 to the head of the machine, above the bed plate 2. Said plate 19 also forms a part of the novel attachment.

The lower end of the arm 17 is forked, and said lower end is provided with a partial cylindrical recess, and the cylindrical head 21 of an arm 23 fits turnably in said recess. Said arm 23 is turnably connected by means of the member 22 to the plate 19. Hence the arms 17 and 23 are rocked in respectively opposite directions.

The lower end of the arm 23 is turnably con-

nected in any suitable manner to a rod 24, which is mounted to reciprocate in bearings 25 which are connected to the underside of the bed plate 2. As shown in Fig. 1, the rod 24 has a cross-fin 5 23a which is received in a vertical slot of the member 23.

An arm 28 is rigidly connected to an end of the rod 24, by means of a collar 26, and a clamping screw 27. Hence the arm 28 reciprocates in 10 unison with the rod 24.

The free end of the arm 28 is yoke-shaped, so as to provide a recess in which the pin 34 of a turnable arm 33 fits more or less snugly. Said arm 33 is located on top of the needle plate 29, 15 which is removably located in a suitable cut-out portion of the cover plate 31. Said needle plate 29 has slots through which the teeth 39 of the feed dog can protrude so as to feed the work C forwardly and in a direction parallel to the axis 20 of arm 33, when said arm is in the median position shown in Fig. 3.

Said needle plate 29 also has a needle slot 32, of the usual type.

The arm 33 is connected to the needle plate 29, 25 by means of a pivot pin 35.

As shown in Fig. 1, the actuating pin 34 extends through an opening of suitable width in the bed plate 2, and it also extends through a corresponding superposed opening in the 30 needle plate 29, so that pin 34 can be moved laterally to-and-fro, in order to turn arm 33. Fig. 1 shows the needle clamp 37, in which the needles 36 and 36a are held.

Referring to Fig. 4 and in particular to Fig. 9, 35 this shows the presser-foot 39 which is connected by means of a bent rod 38a, to the presser-foot holder 38. The usual spring 62 is located around the holder 38, in order to move the holder 38 and presser-foot 39 downwardly to normal 40 position.

The usual cam lever 63 is pivotally connected to the head 1 of the machine by means of the pivot pin 64. The holder 38 is provided with the usual lateral arm 65, which is rigidly connected 45 to said holder 38, by means of the usual collar. Upon moving the cam lever 63 to the position shown in Fig. 9, the holder 38 is held above its normal position. Upon turning the cam lever 63 downwardly, until it clears and it is spaced 50 from the rod 65, the spring 62 presses downwardly upon the collar of rod 65, so as to move the holder 38 and the presser-foot downwardly into normal position.

Fig. 4 shows the holder 38 in the same position 55 which is illustrated in Fig. 9.

Referring to Figs. 1, 4 and 9, a collar 40 is clamped to the needle rod 5, between the lower bearing 12 and the needle clamp 37.

As shown in Figs. 4 and 9, said collar 40 is 60 provided with a perforated extension, in which a rod 41 is slidably mounted. The rod 41 may have its upper end externally threaded and a nut 66 is connected to the upper end of the rod 41, so as to act as a stop for the rod 41.

A helical compression spring 42 is located 65 around the rod 41 and the lower end of said compression spring 42 abuts the enlarged lower end of the rod 41 so that the rod 41 is yieldingly maintained in the position shown in Fig. 4.

Referring to Fig. 5, the underside of the presser-foot 39 is provided with recesses 39a and 39b, which are of unequal width. Said presser-foot 39 is likewise provided with a perforation or cut-out 67, as shown in Fig. 10.

75 A supplemental presser-foot 44 is provided

with spaced end portions 44b, which are located in recesses which are provided in the vertical edges of the rod 38a, which has a generally rectangular cross section. Said recesses are of greater height than the heights of the end portions 44b, so that the supplemental presser-foot 44 has a limited rocking movement relative to the rod 38.

A screw 68 is rigidly connected to the lower adjacent part of the rod 38a and the shank of 10 said screw passes loosely through an opening in the supplemental presser-foot 44 so as to permit said supplemental presser-foot 44 to have a limited movement relative to the rod 38a. The supplemental presser-foot 44 has this limited movement in all directions, relative to the rod 38a.

Said supplemental presser-foot 44 includes a web, which has a front portion 44a, having a slot 44c. The slotted portion 44a of the supplemental presser-foot can move up and down relative to the walls of the slot or opening 67 of the main presser-foot 39.

A spring 69 has its lower end passing around a pin which is connected to the upper surface of the presser-foot 39 and the upper end of said spring 69 abuts the supplemental presser-foot 44, so as to keep the two presser-feet in the normal position illustrated in Fig. 4.

The operation of the device is as follows:

As the main shaft of the machine is turned, a 30 cam 70, which is partially shown in broken lines in Fig. 1, is turned in the usual manner so as to rock the member 9. This causes the frame 60 to be rocked. The needle bar 5 is therefore 35 moved laterally to-and-fro through an arc which is of small curvature. This cam 70 is geared to the main shaft, so that cam 70 rotates at one-eighth the speed of the main shaft.

In the particular embodiment shown, the 40 needle bar makes four reciprocations in forming each series of stitches. That is, the needles 36 and 36a will make their first or left-hand pair of stitches, when said needles are located adjacent the left-hand end of the needle slot 32 (Fig. 3) in making the first stitch of said series. The 45 next pair of stitches of the needles will be made when the needles are at the right of the first mentioned position, and said needles will then make a third pair of stitches and a fourth pair of stitches, the needle 36a being located close to 50 the right-hand end of the needle slot 32, when the fourth pair of stitches is made. The needles will then be given a reverse lateral movement 55 back to the extreme left-hand position, by reversing the turning movement of frame 60. Successive series of stitches are thus formed. Each stitch comprises two or more stitch-elements, since the machine has a plurality of needles.

Each said series or row of stitches is inclined 60 to the preceding series or row of stitches, as shown in Fig. 6. This shows the stitches S which are made by the needle 36 and the stitches Sa which are made by the needle 36a.

The tongue 33 is turned so that the point of 65 said tongue is always directed to a point intermediate the two needles 36 and 36a. This result is secured because the members 17 and 23 are turned in unison with the member 9, which is actuated by said cam 70.

As the needle bar 5 descends, the rod 41 is 70 pressed yieldingly against the supplemental presser-foot 44 so that the member 44a is depressed below presser-foot 39 so as to clamp the work positively, and to prevent the work from 75

shifting while the stitches are being formed. The finger or tongue 33 forms a bight or fold B in the work, and since the stitches S and Sa are formed on opposite sides of the base of said bight, the effect is to produce the rib in the work which is shown in Fig. 7. The rib or bight which is formed in the work, as shown in Fig. 7, is vertically tapered and its narrow end is adjacent the points where the needles pierce the work.

10 The stitches are made with sufficient tension substantially to close the base of said bight, so as to form an upstanding rib in the work.

The type of machine illustrated preferably makes a lock stitch, and the bobbin thread L is also shown in Fig. 7. A single bobbin thread is used for the stitches S and Sa.

I have shown a preferred embodiment of my invention but it is clear that numerous changes and omissions can be made without departing 20 from its spirit.

Referring to Fig. 7, it will be seen that the rib B has a substantially closed base and that the two sides of rib B are very close to each other or abut each other, so as to produce a 25 reinforced upstanding rib.

Referring to Fig. 3, it will be noted that the thin pointed end of the arm 33 is located intermediate the needles when the needles penetrate the work, and this thin pointed end is very close 30 to the needles, as they penetrate the work.

Hence the tension of the sewing thread can form the rib having the above mentioned configuration.

Generally speaking, the novelty of the machine 35 consists primarily in the finger or arm 33, and means for shifting said arm in unison with the lateral to-and-fro movement of the needles so as to form a bight in the work, in order to form the rib B. However, the invention is not limited 40 specifically to the pivoted arm 33, or to the specific mechanism which is shown for turning said arm 33 automatically so that it follows the lateral to-and-fro movement of the needles.

While I have shown a zig-zag formation of the 45 rib B and of the stitches, the invention includes any irregular or ornamental formation of the rib and of the stitches, and it also includes the formation of straight ribs and of straight rows of stitches.

50 It is also obvious that any desired number of ribs can be formed in the work, by using a suitable number of needles, and that the invention is not limited to the manufacture of gloves.

In the embodiment described, I have shown a 55 type of sewing machine in which the work is fed in a single predetermined direction, while the needles are moved laterally to-and-fro, relative to the direction of feed. However, there are types of sewing machines in which the needle plate or other work support is shifted laterally to-and-fro while the needles are merely moved up and down.

Likewise there are certain well known 60 machines in which the direction of feed is varied, so as to make it possible to produce the zig-zag effect or other ornamental effect. Therefore the invention covers machines in which a relative shift is produced by any means so as to produce 65 stitches which follow an irregular or non-rectilinear line or lines, at the opposite sides of the peak of a bight which is formed in the work.

I have not shown the details of the well known 70 cam 70 but it is clear that said cam could be provided with dwell-portions so that there is no

relative lateral shift between the needles and the work, while the needles are being given their work-piercing movement, or while the stitches are being formed.

While there is a shift between the needles and the work during at least a part of the operation of the machine, the needles are given a predetermined work-piercing movement, said movement being vertical in this particular embodiment.

Whenever I refer to a pair of needles I include 10 the use of any desired number of needles.

I claim:

1. A sewing machine comprising a pair of needles, means adapted to actuate said needles to-and-fro in a work-piercing path, automatic 15 means adapted and operative to feed the work relative to the needles and to produce a relative shift between the work and the needles so as to make stitches which follow a non-rectilinear path, a movable bight-forming member, and automatic means adapted and operative to move the bight-forming member so that the end of the bight which is formed thereby is located between the points at which the needles pierce the work. 20

2. A sewing machine comprising a pair of needles, means adapted to actuate said needles to-and-fro in a work-piercing path, automatic 30 means adapted and operative to feed the work relative to the needles and to produce a relative shift between the work and the needles so as to make stitches which follow a non-rectilinear path, a movable bight-forming member, and automatic means adapted and operative to move the bight-forming member so that the end of the bight which is formed thereby is located between the points at which the needles pierce the work. 35

3. A sewing machine comprising a work support, a needle support located above said work support, a pair of needles slidably mounted in said needle support so that said needles can reciprocate vertically, said machine having a frame, said needle support being connected pivotally and on a vertical axis to said frame so that said needle support can be rocked about a vertical axis relative to said frame, a feed-dog means adapted to feed the work forwardly in a single and predetermined direction, automatic means adapted and operative to rock said needle support about said vertical axis so as to form stitches in an irregular line, a bight-forming member pivotally connected to the work support located above the work support and turnable about a vertical axis, and automatic means adapted and operative to turn said member so that the end of said member is always located between the points at which the needles pierce the work. 50

4. A sewing machine comprising a work support, a needle support located above said work support, a pair of needles slidably mounted in said needle support so that said needles can reciprocate vertically, said machine having a frame, said needle support being connected pivotally to said frame and on a vertical axis so that said needle support can be rocked about a vertical axis relative to said frame, feed-dog means 65 adapted to feed the work forwardly in a single and predetermined direction, automatic means adapted and operative to rock said needle support about said vertical axis so as to form stitches in an irregular line, a bight-forming arm 70

75

5 pivotally connected to the work support and located above the work support and turnable about a vertical axis, and automatic means adapted and operative to turn said arm so that the end of said arm is always located between the points at which the needles pierce the work, said arm

having a narrow free end, said end being sufficiently narrow to permit the tension of the stitches substantially to close the base of the bight which is formed in the work by said arm.

JAMES T. DOWDALL.
